(57) **CLAIM**

The ornamental design for a beverage container, as shown and described.

DESCRIPTION

FIG. 1 is a perspective view of the beverage container according to the present design;

FIG. 2 is a perspective view of the beverage container according to the present design;

FIG. 3 is a front elevational view of the beverage container, the back elevational view being a minor image thereof;

FIG. 4 is a left side elevational view of the beverage container;

FIG. 5 is a right side elevational view of the beverage container; and,

FIG. 6 is an exploded perspective view thereof.

The broken lines in the drawings are included for the purpose of illustration and form no part of the claimed design.
